UNITED STATES PATENT OFFICE.

WILLIAM S. GRAHAM, OF CANTON, ILLINOIS, ASSIGNOR TO PARLIN AND ORENDORFF COMPANY, OF CANTON, ILLINOIS, A CORPORATION OF ILLINOIS.

RIDING BEET-CULTIVATOR.

No. 885,469.

Specification of Letters Patent. Patented April 21, 1908.

Application filed December 4, 1907. Serial No. 405,072.

To all whom it may concern:

Be it known that I, WILLIAM S. GRAHAM, a citizen of the United States, residing at Canton, in the county of Fulton and State of Illinois, have invented certain new and useful Improvements in Riding Beet-Cultivators, of which the following is a specification, reference being had to the accompanying drawings.

10 My invention relates to riding beet-cultivators, and particularly to the kind of cultivators known as four-row cultivators, and one of its objects is to provide a new and improved wheel frame for such cultivators capable of being easily disconnected for shipping or other purposes.

Another object is to provide a new and improved means by which the front carrying wheels can be adjusted laterally so as to 20 travel between the rows at different distances apart.

Another object of my invention is to provide new and improved means for tilting the gang frames carrying the cultivating appliances with relation to the carrying frame.

Another object of my invention is to provide new and improved lever mechanism for raising and lowering the gang frames, either together or independently of one another.

30 My invention has for a further object the improvement of such cultivators in sundry details hereinafter pointed out.

In the accompanying drawings,—Figure 1 is a side elevation, showing the right-hand wheel removed; Fig. 2 is a top or plan view; Fig. 3 is an enlarged detail, being an isometric view of the carrying frame; Fig. 4 is a detail, being a plan view of the carrying frame and showing the foot-lever mechanism for 40 angling the wheels; Fig. 5 is a detail, being an end view of the wheel-supporting bracket and sleeve with the rim and most of the spokes of the wheel being broken away; Fig. 6 is a vertical section on line 6—6 of Fig. 5; Fig. 7 is a detail, being a side elevation, partially in section, of a portion of the front frame, the seat-beams and cultivating mechanism, showing the lever mechanism for raising and lowering the cultivator gangs; Fig. 8 50 is a detail, being a horizontal section of a portion of the seat-beams, showing the means for mounting the levers; Fig. 9 is an enlarged detail, being a plan view, showing

the lever mechanism; Fig. 10 is a side elevation of the parts shown in Fig. 9, partially in 55 vertical section; and Fig. 11, is an enlarged detail, being a view of one of the hand-levers and notched segments.

Referring to the drawings,—the front or carrying frame of the machine is composed 60 of a front bar 12 and rear bar 13 and a brace bar 14 secured to the bars 12 and 13. The frame is also braced by other parts hereinafter pointed out.

15 indicates hangers, which are bifurcated 65 at their lower ends to receive the forward ends of the draw-bars hereinafter described. The brackets 15 are bolted or otherwise secured to the front cross-bar 12 of the carrying frame.

16 indicates braces, which are bolted or otherwise secured at their forward ends to the lower part of the hangers 15 and extending diagonally upward and backward are bolted or otherwise secured at their rear ends 75 to the rear cross-bar 13, serving to brace the hangers 15.

17 indicates a tongue, which is mounted preferably by a suitable bracket 18 on the front bar 12 to which it is braced by 80 brace-rods 19 whose forward ends are bolted or otherwise fastened to the tongue 17, and which extending diagonally outward and backward are secured at their rearward ends to the outer pair of brackets 15, preferably 85 by having their rear ends bent and inserted through suitable openings in the brackets and held in place by cotter-pins 20.

21 indicates brackets, which are provided at their front ends with a shoulder 22 adapted 90 to be removably bolted to the front bar 12 and at their rear ends with a clip 23 adapted to be secured upon the rear bar 13 and locked in place by a bolt 24.

25 indicates a sleeve, which is secured to 95 the bracket 21 and acts as a journal for the vertical portion of the wheel spindle hereinafter described.

The brackets 21, the shoulders 22, clips 23, and sleeve 25 are preferably formed integral 100 with one another, but they may, of course, be rigidly secured together in any other appropriate manner.

26 indicate braces, which are secured at their outer ends to the lower ends of the 105 sleeves 25 and extending upwards and in-

wards are bolted at their inner ends to the rear cross-bar 13 to act as braces for the sleeves 25.

27 indicate brackets, which are bolted or 5 otherwise secured to the inner side of the rear bar 13, near the ends thereof.

28 indicates brackets, which are fastened by clips, or in any other appropriate manner, to the rear cross-bar 13 near the center 10 thereof, and are provided with downward-extending arms 29 which are recessed at their lower ends, as best shown in Fig. 3. The brackets 27—28 are provided with suitable openings which act as a journal for the rock- 15 shaft hereinafter described.

30 indicates a truss-rod whose outer ends are bolted or otherwise secured to the brackets 27, and which bears against the arms 29 of the brackets 28 in the notched 20 lower ends thereof.

31 indicates hounds, the forward ends of which rest above and are secured to the cross-bar 12 and which pass beneath the rear bar 13, secured thereto by clips 32, or in any 25 other appropriate manner.

33 indicates seat-bars, whose forward ends are bolted to the hounds 31 and which extend backward, coming closer together as they approach their rear ends in which is mounted a 30 sleeve 34 which supports the upright spindle of the caster-wheel 35 so as to permit the caster-wheel to turn freely in said sleeve. The caster-wheel and its spindle are of ordinary and well-known form and description 35 and need no further description here.

36 indicates a seat, which is mounted upon the rear ends of the seat-bars 33.

37 indicates the carrying wheels, which are mounted upon a spindle 38 provided with an 40 upright portion 39 which is journaled in the sleeve 25, as best shown in Fig. 6.

40 indicates a two-part clip, which is mounted upon the spindle 38, extending part way up the vertical portion 39. The outer 45 end is formed with a peripheral interior groove 41 which is adapted to receive a circular flange 42 on the hub 43 of the carrying wheel.

44 indicates an arm, whose lower end is 50 secured to the clip 40 by means of suitable bolts which pass through the lower end of the arm, through the clip 40 and through the upright portion 39 of the wheel spindle 38. The arm 44 extends diagonally upward and 55 backward.

45 indicates a connecting-bar which is pivotally connected at its ends to the arms 44.

46 indicates brackets which are bolted or otherwise secured to the inner sides of the 60 seat-beam 33.

47 indicates bell-crank levers, which are pivotally mounted on the brackets 46. One end of each of the bell-crank levers 47 projects forwardly and is pivotally connected to 65 the cross-bar 45, as is best shown in Figs. 2

and 4. The other arm of each bell-crank lever extends laterally outward and is provided at its end with a foot-rest 48. It will be obvious that the driver by the pressure of the foot upon one or the other of the foot- 70 rests 48 will cause the bell-crank levers to rock, moving the arm 45 laterally to one side or the other, and thus angling the wheels, as is best shown in Fig. 4.

By loosening the bolts by which the forward ends of the brackets 21 are secured to the front frame and the bolts by which the inner ends of the braces 26 are secured to the rear cross-bar 12, and by loosening the clips 24, the brackets 21 may be moved inwards to- 75 wards and away from the center of the machine and locked in any desired position, the front and rear bars receiving a number of perforations for the insertion of the bolts. By this means the wheels may be laterally 80 adjusted towards or away from each other to suit different widths.

It will be obvious from the above description that by unfastening the bolts by which the seat-beam is secured to the hounds the seat- 9 beam may be separated from the front frame; also that the wheels may be readily removed, if desirable, for convenience of shipment or otherwise.

The gang frame for carrying the cultivating 95 appliances is composed of cross-bars 49—50 secured together by cross-bars 51 at their outer ends.

52 indicates clamps, which are bolted or otherwise secured to the cross-bars 49—50 in which are adjustably clamped the standards 53 of the cultivating shovels 54—55 in such a way that their position may be varied 100 therein and may be securely clamped in any desired position by means of bolts 57. I have shown in my machine two kinds of cultivating shovels,—54, known as "weeders", and 55 generally known as "duck-feet", but, of course, any other kind of shovels or cultivating appliances may be used.

58 indicates draw-bars, whose forward ends are pivotally mounted in the lower bifurcated ends of the hangers 15 and whose rear ends are bolted or otherwise secured to the gang frame.

59—60 indicate rock-shafts, one upon each side of the machine, journaled in the brackets 27—28. The outer ends of the rock-shafts 59—60 are bent at right angles to form arms 59^a—60^a which extend backwardly 120 substantially horizontally.

61 indicates links, whose upper ends are pivotally connected with the rearward ends of the arms 59^a—60^a, and whose lower ends pass through lugs 62 bolted or otherwise secured to the draw-bars 58, and are prevented from being lifted out of the lugs by means of cotter-pins or other suitable well-known device.

63 indicates spiral expansion springs, 130

whose upper end bears against a suitable shoulder on the link 61 and whose lower end bears upon the upper surface of the lugs 62, the function of the spring being to yieldingly hold the shovels in the ground.

It will be obvious from the above description that if both the rock-shafts 59—60 are rocked the gang frame will be lifted parallel to itself throughout its length, raising or lowering all the shovels simultaneously, and that if one of the rock-shafts only is rocked the gang frame will be correspondingly raised or lowered at one end, tilting the same so as to keep it in proper relation with the ground regardless of the tilt of the carrying frame. The rock-shafts are rocked by levers 64—65, which are connected, respectively, by links 66—67 and to downward-depending arms 68—69 which are clamped or otherwise rigidly secured to a squared or non-circular portion at the inner ends of the rock-shafts 59—60.

71 indicates a notched segment, which is bolted to one of the seat-frame bars 33 and is provided with a hollow portion 72 in which is seated one end of a sleeve 73, as is best shown in Fig. 8. The other end of the sleeve 73 is seated in a block 74, which is held in position by the bolting together of the parts 30 hereinafter described.

76 indicates a notched segment provided with a sleeve or hub portion 76^a by means of which it is rotatably mounted on the sleeve 73, the whole being bolted together in position between the bars 33 by a bolt 75. The lever 65 is bolted or otherwise rigidly secured to the segment 76. The lever 64 is pivotally mounted on the segment 76 by means of a pivot-pin 77. Each of the levers 40 is provided with the usual spring-seated latch 78—79 operated, respectively, by the usual hand-levers 80—81 and links 82—83. The latch 78 on the lever 64 engages the notched segment 76 and the latch 79 on the lever 65 engages the fixed notched segment 71.

It will be obvious from the above description that if the lever 65 is released from the fixed segment 71 and the lever 64 engaged with the segment 76 both levers will be 50 swung together and both rock-shafts will be simultaneously lifted, lifting the gang frame throughout its entire length parallel to itself. If, however, both hand-levers 80 and 81 are operated to disengage the latches 78 and 79, the levers 64—65 may be operated so as to rock either of the rock-shafts, or one rock-shaft in one direction and the other in the other, correspondingly tilting the gang frame from its horizontal position, as may be desired. The action of the levers in raising and lowering the frames is assisted by the springs 84, which are connected at their forward ends to suitable brackets 85 on the front bar 12 of the carrying frame and at 65 their rearward ends to brackets 86 which are

secured to and project upward from the arms 59^a—60^a of the rock-shafts 59—60. The forward ends of the springs 84 are preferably connected to the brackets 85 by means of an eye-bolt 87, the eye of which receives the forward end of the coiled spring and which may be adjusted so as to vary the tension of the spring by means of a nut 88 screwed upon the screw-threaded forward end of the eye-bolt 87.

That which I claim as my invention, and desire to secure by Letters Patent, is,—

1. In a cultivator, the combination with a front frame consisting of two parallel transverse bars, brace bars and hounds secured to said cross-bars, wheel carrying brackets carried by said cross-bars and adjustable laterally thereon, of a rearwardly-extending seat-support removably secured to said hounds, downwardly-extending hangers secured to said front frame, a gang-carrying frame, and draw-bars mounted on said gang-carrying frame and pivotally secured at their front ends to said hangers.

2. In a cultivator, the combination with a carrying frame, a gang frame, and draw-bar connections between said gang frame and said carrying frame, a pair of rock-shafts having rock arms at their outer ends and journaled in said carrying frame, link connections between said rock arms and the outer ends of said gang frame, a segment secured to said gang frame, a lever pivoted to said segment, a connection between said lever and one of said rock arms, a second segment rigidly mounted on said lever, a second lever pivotally mounted on said second segment, and a connection between said second lever and the other rock-shaft.

3. In a cultivator, the combination with a carrying frame, a gang frame, and draw-bar connections between said gang frame and said carrying frame, a pair of rock-shafts having rock arms at their outer ends and journaled in said carrying frame, link connections between said rock arms and the outer ends of said gang frame, a segment secured to said carrying frame, a lever pivotally connected with said segment, a latch adapted to adjustably lock said lever to said segment, a connection between said lever and one of said rock-shafts, a second segment rigidly mounted on said lever, a second lever pivoted to said second segment, latch connections adapted to adjustably lock said second lever and said second segment, and a connection between said second lever and the other rock-shaft.

4. In a cultivator, the combination with a carrying frame, a gang frame, and draw-bars connecting said gang frame and said carrying frame, of a pair of rock-shafts journaled in said carrying frame and having rock arms at their outer ends, link connections between said rock arms and the outer ends of said gang frame, and lever mechanism adapted to

either rock said rock-shafts simultaneously or independently.

5. In a cultivator, the combination with a carrying frame, a gang frame and draw-bars connecting said gang frame with said carrying frame, of a pair of rock-shafts journalized in said carrying frame and having rock arms at their outer ends, link connections between said rock arms and the outer ends of said 10 gang frame, a swinging lever carried by said carrying frame and connected with one of said rock-shafts, and mechanism connected with said lever and with the other of said rock shafts, whereby both the said rock- 15 shafts may be rocked simultaneously.

6. In a cultivator, a carrying frame consisting of two parallel transverse bars, brace bars, hounds secured to said carrying bars, wheel-supporting brackets carried by said 20 transverse bars and adjustable laterally thereon, a rearwardly-extending seat-support removably secured to said hounds and having a caster wheel supported at its outer end, downwardly-depending hangers secured

to one of said cross-bars, and braces connecting the lower ends of said hangers with the other of said cross-bars. 25

7. In a cultivator, the combination with a carrying frame, wheel-supporting brackets mounted in said carrying frame and adjustable laterally thereon, vertically-disposed sleeves secured to said brackets, wheel spindles having vertical portions journalized in said sleeves, carrying wheels mounted on said wheel spindles, rearwardly extending arms rigidly secured to said wheel spindles below said sleeves, a cross-bar pivotally connected at its ends with said rearwardly-extending arms, bell-crank levers mounted on said carrying frame and having forwardly-extending arms pivotally connected to said cross-bar and having foot-rests on their laterally-extending arms. 30 35 40
